UNITED STATES PATENT OFFICE.

BERNHARD C. MOLL, OF CHICAGO, ILLINOIS.

DENTAL CASTING-MACHINE.

1,201,606.

Specification of Letters Patent. Patented Oct. 17, 1916.

Application filed August 28, 1911. Serial No. 646,413.

To all whom it may concern:

Be it known that I, BERNHARD C. MOLL, a citizen of the United States of America, and resident of Chicago, Illinois, have invented 5 a certain new and useful Improvement in Dental Casting-Machines, of which the following is a specification.

My invention relates to dental casting machines, and more particularly to a dental 10 casting machine in which both pressure and vacuum are employed in the casting operation.

One of the objects of my invention is to provide an improved casting machine in 15 which pressure can be applied at the top of the flask and simultaneously the lower part of the flask can be connected with the vacuum chamber.

Another object of my invention is to provide 20 an improved flask which can be readily opened to remove the casting inlay, and which can be fastened together so as to form an air-tight flask.

A further object is to provide suitable 25 adjusting means whereby flasks of various sizes can be readily substituted without interfering with the effective operation of my improved apparatus.

These and other objects of my invention 30 will be more readily understood by having reference to the accompanying drawings, in which similar reference numerals indicate like parts, and in which—

Figure 1 is a side elevation partly in section of my improved apparatus. Fig. 2 is a plan view of the same. Figs. 3, 4, 5, 6 and 7 are detail views of various parts of my apparatus. Fig. 8 is a cross-sectional view of a part of my improved flask.

Having reference to the drawings, I have 40 there shown a vacuum chamber 10 within which is mounted a suitable pump 11 for creating a vacuum within this chamber in any well known manner. Mounted in one 45 end of this vacuum chamber is a removable threaded casting 12 within which rests the cone valve 13 carried by the spindle 14, which spindle is provided with a laterally extending end 15. This spindle passes 50 through the elbow of the pipe 16, which pipe extends horizontally to a point near the center line of the vacuum chamber, at which point it turns upwardly and is provided with a cup-shaped bearing 17 within which rests the lower half 18 of the flask. The pipe 16 is preferably supported upon the

flat surface 19 of the vacuum chamber, so as to form a more rigid structure. Mounted on the opposite end of the vacuum chamber is a movable standard 20, which is adapted 60 to slide in a suitable guide-way 21 mounted upon the end of the vacuum chamber 10. This movement of the standard 20 is accomplished by means of the rack 22 mounted upon the inside of the standard 20 and the 65 pinion 23 which meshes with this rack, which pinion is operated by means of the thumb-nut 24. A locking screw 25 is provided whereby the standard can be held in any desired position. Upon the upper end 70 of this standard 20 is mounted a yoke 26. Pivotally mounted within this yoke is a sleeve 29^a which surrounds an arm 27, which arm is provided with an operating handle 28. A part of this arm is hollow to provide 75 an air-passage 29 which arm 27 terminates in a cone-shaped valve member 30 within the pivotal bearing 31. This cone-shaped valve is provided with an opening 32 which is adapted to be rotated so as to engage with 80 the passage-way 33 which connects with the air-supply pipe 34. I have shown a controlling valve 35 and a pressure gage 36 connected with this air-supply pipe, whereby I am able to regulate the pressure of the 85 air which is supplied to the system. From the construction of this cone valve it will be seen that the valve may be opened and closed by merely rotating the handle 28, whereby the opening 32 can be brought into 90 engagement with the passage-way 33. The opposite end of this air-passage 29 terminates in an angular portion 30^a which engages with the opening in the top of the cap 38. Extending downwardly from the operating 95 handle there is a rod 37 which is adapted to engage with the laterally extending end 15 of the spindle 14, whereby when the handle 28 is rotated around the longitudinal axis of arm 27 the rod 37 bears against the end 100 of the extension 15, thereby rotating the spindle 14 so as to operate the cone valve 13, thereby controlling the connection between the pipe 16 and the vacuum chamber.

The cap 38, which is adapted to fit over 105 the top of the flask, is carried by the sleeve 29^a. This cap is provided with an opening which is connected with the air-passage 29, this opening being flared at its lower portion, and being provided with a perforated 110 plate to diffuse the air as it passes through the same. The flask comprises the lower

section 18 the upper edge of which section is V-shaped, while the upper section 18^a is provided with a corresponding V-shaped groove, whereby an air-tight connection is made when these two sections are brought together. These two sections are held in place by the bolts 39 which pass through the lugs 40 and 41 upon the upper and lower sections. By having this flask divided horizontally I am able to obtain ready access to the casting, and it is likewise easier to fill the flask with the investment material. I have shown a blow-pipe 42 pivoted in the yoke member 26 which blow-pipe can be brought into position so as to melt the metal placed in the top of the flask, and can be then swung out of the way when not in use.

In the operation of my improved device, the flask is first filled with the investment material and a wax model absorbed in the usual manner, leaving the mold space with a sprue opening through the top. This mold space is preferably so positioned in the flask that the lower half is in the lower section 18 of the flask, while the upper half is in the upper section. The metal is then placed in the upper flask above the sprue opening, as shown, and the blow-pipe then brought into position to melt the metal. The metal having been melted, the blow-pipe is then swung out of position and the cap 38 brought down upon the top of the flask by means of the operating handle 28. When this cap has been brought in position and is fitted securely over the top of the flask, the handle 28 is then rotated so as to open communication with the air pressure through the passage 29, and with the vacuum chamber through the pipe 16, thus simultaneously causing the pressure and vacuum to act upon the molten metal, and forcing the same through the sprue opening into the mold. It will be seen that in order for the cap 38 to fit securely upon the flask it is necessary that the arm 27 be substantially horizontal when in its lowered position. As the various flasks which may be employed are of varying height, it therefore becomes necessary to adjust the height of this arm 27, and this is accomplished by adjustment of the spindle 20 by means of the thumb-nut 24, as heretofore described.

A further advantageous feature of my invention is that the air pressure is not turned on until after the cap has been securely brought in place so that there is no danger of the air leaking through the sides of the cap, due to the fact that the pressure is turned on before the cap is properly in position upon the flask.

While I have illustrated my invention in connection with a combined pressure and vacuum system, it is to be understood, of course, that if desired it could be used with a pressure system alone, or with a vacuum system alone, although I find that better results are obtained by the use of the combined pressure and vacuum. Likewise many other modifications and changes will readily suggest themselves to anyone skilled in the art.

What I claim as my invention is:

1. In a dental casting machine, a mold flask, a cap adapted to be swung to and from the top of said flask, an arm carrying said cap, and means for vertically adjusting said arm.

2. In a dental casting machine, a source of compressed air, and a vacuum chamber, a flask, a cap adapted to be swung to and from said flask, and means for simultaneously opening communication between said pressure and vacuum chambers after said cap has been brought into position upon said flask.

3. In a dental casting machine, a source of compressed air and a vacuum chamber, a flask, a cap carried by a pivoted arm adapted to be swung to and from said flask, and means controlled by said arm after said cap has been brought into position upon said flask, for simultaneously opening communication between said source of compressed air and said vacuum chamber.

4. In a dental casting machine, a vacuum chamber, a flask supported upon and having communication with said chamber, a standard adjustably mounted upon said chamber, an arm pivotally mounted in the upper end of said standard, and a cap carried by said arm and adapted to be swung to and from the top of said flask.

5. In a dental casting machine, a source of compressed air and a vacuum chamber, a flask supported upon said chamber, a standard adjustably mounted upon said chamber, an arm pivotally mounted in the upper end of said standard, a cap carried by said arm and adapted to be swung to and from the top of said flask, and means actuated by said arm when the cap is moved into position on said flask to simultaneously open communication between said flask and said source of compressed air and said vacuum chamber.

Signed by me at Chicago, Illinois, this 19th day of August 1911.

BERNHARD C. MOLL.
